UNITED STATES PATENT OFFICE.

JOHN N. HOLLIS, OF MACON, GEORGIA.

CLEANING-MACHINE.

978,749.

Specification of Letters Patent. Patented Dec. 13, 1910.

Application filed May 9, 1910. Serial No. 560,131.

To all whom it may concern:

Be it known that I, JOHN N. HOLLIS, a citizen of the United States, residing at Macon, in the county of Bibb, State of Georgia, have invented certain new and useful Improvements in Cleaning-Machines; and I do hereby declare the following to be a full, clear, and exact description of the invention, such as will enable others skilled in the art 10 to which it appertains to make and use the same.

The invention relates to a cleaning apparatus and more particularly to the class of machines for cleaning typewriters, adding 15 machines or other analogous structures.

The primary object of the invention is the provision of a machine in which cleaning fluid will be discharged into a brushing element that may be manually manipulated to 20 clean the various adjunct parts of a machine, the cleaning fluid being adapted to cleanse the parts as the brush is acting thereon.

Another object of the invention is the provision of a machine of this character in which a brush has connection with a cleansing fluid tank which fluid therein is subjected to air pressure so as to dispense the fluid through the brush as the latter is being 30 handled by a person for cleaning machine parts.

A still further object of the invention is the provision of a machine in which a cleaning brush is supported for rotation upon a 35 flexible fluid supply tube having connection with a tank containing cleansing fluid which latter is discharged under air pressure into the bristles of the brush whereby on rotation of the brush the parts of machinery may 40 be readily and conveniently cleaned both by the cleansing fluid and brush.

A still further object of the invention is the provision of a machine of this character which is simple in construction, thoroughly 45 reliable and efficient in operation and inexpensive in manufacture.

With these and other objects in view the invention consists in the construction, combination and arrangement of parts as will be 50 hereinafter more fully described, illustrated in the accompanying drawings disclosing the preferred form of embodiment of the invention and pointed out in the claims hereunto appended.

55 In the drawings:—Figure 1 is a vertical longitudinal sectional view through a ma-

chine constructed in accordance with the invention, the adjunct parts thereof being shown partly broken away. Fig. 2 is a similar view showing the outer casing removed 60 with the leg portions of the machine in position for supporting the same. Fig. 3 is a top plan view thereof. Fig. 4 is an end elevation of the machine the same being in case. Fig. 5 is a vertical transverse sectional 65 view on the line 5—5 of Fig. 1. Fig. 6 is a sectional view through the brush and its connections with the motor and tank. Fig. 7 is a sectional view on the line 7—7 of Fig. 6. Similar reference characters indicate cor- 70 responding parts throughout the several views in the drawings.

Referring to the drawings by numerals 10 designates generally a casing having an open top, the casing being preferably of rectangular shape although it may be of any other desirable shape and constructed of any suitable material and arranged within the same upon its bottom 11 is a motor 12, the same being preferably an electric current motor 80 having a horizontally disposed rotatable drive shaft 13 to one end of which is fixed a belt pulley 14 over which is trained a belt 15 the latter also being trained over a pulley 16 fixed to one end of the rotatable spindle 85 17 of a stationary head stock 18 the same being fixed at one end of a bed 19 upon which is adjustably mounted a tail stock 20 adapted to co-operate with the head stock for holding platen of typewriters or the like 90 whereby they may be treated as the occasion may require, the bed 19 being secured to one side wall of the casing 10 near its open top.

95 Adjacent to the motor 12 and rising within the casing 10 from the bottom 11 thereof is an air compressor or pump 21 the same being of the ordinary type in which is mounted a reciprocating piston 22 the stem of which is eccentrically connected to a rotatable disk 23 fixed to a short shaft 24 the same having also fixed thereto a pulley 25 over which is trained a belt 26 the latter also being trained over a pulley 27 fixed to the driving shaft 13 of the motor so that 100 through the medium of this belt 26 the pump may be actuated.

Connected to the pump 21 through the medium of an air pipe 28 is an air storage tank 29 the same being superimposed upon 110 the bottom 11 of the casing 10 and rises vertically therefrom so that air from the

pump may be discharged into the storage tank for a purpose as will be hereinafter more fully described.

5 Adjacent to the storage tank 29 is a receptacle 30 adapted to receive cleansing liquid such as gasoline, benzine or the like, the receptacle 30 being connected with the storage tank by a pipe 31^a communicating therewith, the pipe 31^a being adapted to deliver compressed air from the storage tank above the surface of the cleansing liquid within the receptacle 30 to maintain it under pressure. Leading from the bottom of the receptacle 30 is a delivery elbow 31^b 10 the latter communicating directly with a flexible tube 32 the inner end of which is suitably fixed to one end wall of the casing 10 and disposed within this tube 32 is a hollow rotatable flexible tube 33 the inner end of which is suitably fixed to the driving shaft 13 of the motor 12 and at the point where the tube 33 passes through the wall of the delivery elbow 31 there is provided a stuffing gland 34 which prevents the cleansing liquid from leakage at this particular point. This flexible tube 33 for that portion of its length confined within the elbow 31 is provided with suitable elongated slots or openings 35 to permit the entrance of the 15 cleaning liquid from the receptacle 30 into the said tube to be discharged therefrom between the bristles of a rotatable brush 36 the latter being detachably connected to the outer end of the flexible tube 33, the said 20 brush being adapted for cleaning machinery or the like. The flexible tube 33 carries a cut off valve 37 to regulate and control the fluidity of the liquid from the receptacle to the brush. Hinged to the bottom 11 of the 25 casing 10 are foldable legs 38 the said legs serving to support the casing 10 elevated a distance from the floor when the machine is in operation.

The casing 10 is adapted to be removably 40 fitted in a carrying case 39 the same being provided with a removable lid or cover 40 and the body of this case is of a depth substantially one-half of the casing 10. Disposed longitudinally of the case and superposed a distance from its bottom are a plurality of slats 41 the same being suitably secured to the end walls of the said case and these slats are adapted to support a typewriter or other machine to be cleaned, the 45 slats permitting the cleaning liquid to be delivered through the spaces therebetween on to the bottom of the case where it may be drained through a drain-cock 42 from the said case. The lid or cover 40 is provided 50 with suitable catches whereby it may be detachably locked to the body of the case. Also this lid is provided with a handle 43 which permits the machine to be carried in the hand of a person for conveying it from 55 one locality to another. In the pipe 31 lead-

ing from the storage tank 21 to the cleaning liquid tank 30 is a cut off valve 43' so that the supply of air can be regulated from the said storage tank to the liquid tank when desired. One side wall of the case 39 is connected to 70 the end walls and the bottom of said case by bellows sections 44 whereby the body of the case may be extended to increase its interior capacity.

What is claimed is:—

1. An apparatus of the class described, a casing, a motor supported upon the bottom of the casing, an air storage tank, a fluid receptacle in communication with the tank whereby the contents will be maintained under pressure, a pump communicating with the storage tank for supplying air thereto, a hollow rotatable tool shaft communicating with said fluid receptacle, and driven connections between the motor, pump and shaft 85 whereby the said pump and shaft will be simultaneously operated.

2. An apparatus of the class described, a casing, a motor supported upon the bottom of the casing, an air storage tank, a fluid receptacle in communication with the tank whereby the contents will be maintained under pressure, a pump communicating with the storage tank for supplying air thereto, a hollow rotatable tool shaft communicating 90 with said fluid receptacle, driven connections between the motor, pump and shaft whereby the said pump and shaft will be simultaneously operated, and means controlling the communication between the air storage tank 95 and the fluid receptacle.

3. An apparatus of the class described, a casing, a motor supported upon the bottom of the casing, an air storage tank, a fluid receptacle in communication with the tank 100 whereby the contents will be maintained under pressure, a pump communicating with the storage tank for supplying air thereto, a hollow rotatable tool shaft communicating with said fluid receptacle, driven connections 105 between the motor, pump and shaft whereby the said pump and shaft will be simultaneously operated, means controlling the communication between the air storage tank and the fluid receptacle, and a valve arranged 110 within the tool shaft.

4. An apparatus of the class described, a casing, a motor supported upon the bottom of the casing, an air storage tank, a fluid receptacle in communication with the tank 120 whereby the contents will be maintained under pressure, a pump communicating with the storage tank for supplying air thereto, a hollow rotatable tool shaft communicating with said fluid receptacle, driven connections 125 between the motor, pump and shaft whereby the said pump and shaft will be simultaneously operated, means controlling the communication between the air storage tank and the fluid receptacle, a valve arranged within 130

the tool shaft and a flexible non-rotatable shaft 2 inclosing said rotatable shaft.

5. An apparatus of the class described, a casing, a motor supported upon the bottom 5 of the casing, an air storage tank, a fluid receptacle in communication with the tank whereby the contents will be maintained under pressure, a pump communicating with the storage tank for supplying air thereto, a 10 hollow rotatable tool shaft communicating with said fluid receptacle, driven connections between the motor, pump and shaft whereby the said pump and shaft will be simultaneously operated, means controlling the 15 communication between the air storage tank and the fluid receptacle, a valve arranged within

the tool shaft, a flexible non-rotatable shaft 2 inclosing said rotatable shaft, a bed plate fixed to one side wall of the casing, a stationary stock having a rotatable spindle 20 mounted upon the bed plate an adjustable tail stock movable toward and away from the stationary stock and supported upon the bed plate and driven connection between the motor and the spindle of the stationary 25 stock whereby it may be rotated.

In testimony whereof, I affix my signature, in presence of two witnesses.

JOHN N. HOLLIS.
